CLAIM

The ornamental design of a wooden barbecue grill cart with curved arch supports, as shown and described.

DESCRIPTION

FIG. 1 is a perspective view showing my new wooden barbecue grill cart with curved arch supports;

FIG. 2 is a left side elevational view thereof;

FIG. 3 is a right side elevational view thereof;

FIG. 4 is a front elevational view thereof.

FIG. 5 is a rear elevational view thereof,

FIG. 6 is a top plan view thereof; and,

FIG. 7 is a bottom plan view thereof.

The details shown in broken lines in FIGS. 1-7 are for illustrative purposes only and form no part of the claimed design. Portions of the claimed design obscured by broken lines form no part of the claimed design.

1 Claim, 5 Drawing Sheets
